US00D965961S

(12) United States Design Patent (10) Patent No.: US D965,961 S
Herath et al. (45) Date of Patent: * Oct. 11, 2022

(54) SHOE

(71) Applicant: adidas AG, Herzogenaurach (DE)

(72) Inventors: Ben Herath, Herzogenaurach (DE);
Moritz Hoellmueller, Herzogenaurach (DE); Stephen Dobson, Herzogenaurach (DE); Sam Handy, Herzogenaurach (DE); Fabio Villa, Herzogenaurach (DE)

(73) Assignee: adidas AG, Herzogenaurach (DE)

() Term: 15 Years

(21) Appl. No.: 29/773,594

(22) Filed: Mar. 10, 2021

Related U.S. Application Data

(63) Continuation of application No. 29/693,455, filed on Jun. 3, 2019, now Pat. No. Des. 915,055.

(30) Foreign Application Priority Data

Dec. 3, 2018 (EM) 005841939

(51) LOC (13) Cl. 02-04
